ABSTRACT

The rotary ring of a log barker has a flaring mouth carrying limb-cutting bits in radial planes. Hooked ends of swinging arms rotate around a log as it is moved lengthwise to scrape off the bark. Bark and limb pieces fall into a hog having stationary shearing bars cooperating with rotary shearing bars carried above a plate rotating about a vertical axis. Hogged material dropping through apertures in the plate is swept out of the casing by vanes carried by the rotor.

LOG BARKER DELIMBER AND REFUSE-REDUCING MECHANISM

This application is a division of application Ser. No. 627,067, and now U.S. Pat. No. 3,536,265 for Log Barker Refuse-Reducing Mechanism.

A principal object of the invention is to remove limbs from logs being barked more readily and effectively and with less interference with the barking operation than has been experienced previously.

Another object is to remove bark and limb refuse effectively from a log barker so as to eliminate the necessity of cleaning the barker periodically.

An additional object is to comminute discrete fragments of bark and limb refuse removed from a log passing through a barker which can be spread as a mulch or transported readily for disposal.

It is also an object to utilize the present mechanism in lieu of a refuse conveyor located beneath a log barker.

More particularly, the invention relates to an improved type of limb and knot paring mechanism having inclined bits with an obtuse-angled cutting edge. A refuse hog beneath the barker includes a bridge carrying stationary cutting bars offset from radial positions toward approaching rotary shearing bars, the shearing edges of which rotary bars preferably are offset forwardly in their direction of rotation from radii of the hog rotor. The hogged material drops through apertures in the hog rotor immediately ahead of the rotary shearing bars. Radial vanes carried by the rotor sweep the hogged material around the lower portion of the rotor and out through a tangentially located discharge port.

FIG. 1 is a longitudinal vertical section through a log barker and refuse-reducing mechanism of the present invention.

FIG. 2 is an elevation of the barker ring assembly viewed from the discharge side, with parts broken away.

FIG. 3 is a corresponding elevation of the barker ring assembly viewed from the feed side.

FIG. 4 is an enlarged vertical longitudinal section through the barker ring assembly.

FIG. 5 is a detail bottom plan of a portion of a limb cutter bit taken on line 5-5 of FIG. 4, FIG. 6 is a detail section on line 6-6 of FIG. 5, and FIG. 7 is a section on line 7-7 of FIG. 5.

FIG. 8 is a horizontal section taken along line 8-8 of FIG. 1, showing the refuse hog.

FIG. 9 is a top perspective of a fragmentary portion of the refuse hog.

The refuse-reducing mechanism of the present invention can be applied to various types of rotary ring log barkers, representative examples of which are shown in Nicholson U.S. Pat. No. 2,802,494 and in FIGS. 1, 2, 3 and 4, in particular, of the drawings of this application. Logs L are fed lengthwise to such a barker by a feed conveyor 1 and the barked log is withdrawn from the barker by a discharge conveyor 2. The barker ring assembly is mounted on a plate 3 which can be suitably mounted and guided for elevational movement so that the center of the rotary barker ring 4 will coincide with the axis of the log L being barked. The barker ring is rotated around the log by a drive chain 5 engaging a drive sprocket 6 and teeth provided along the circumference of the barker ring.

Each log is fed through the throat 7 of the barker ring 4 to be engaged by scraper tips of the barker arms 8 which are mounted on the barker ring by pivots 9. These barker arms are swung in a direction about such pivots to press their scraping ends against the log by hydraulic jacks 10. Pressure of the barking tips of the arms against the log is maintained by air under pressure in expandible air chambers 11 which are in communication with the respective jacks 10. Such log barker mechanism described thus far in detail is not part of the present invention, but is simply representative of a typical rotary ring barker to which the present invention can be applied.

Projecting from the feed side of the rotary barker throat 7 is an annular flange or collar 12 forming a flared mouth through which a log L is moved by the feed conveyor 1 into the barker ring throat 7. The angle between any portion of such mouth in

a radial plane and the axis of the barker ring 4 should be between 45° and 60° and preferably is about 55°. On the flaring inner face of collar 12 are mounted elongated cutter bits 13 having their lengths disposed substantially in radial planes.

5 These cutter bits are spaced circumferentially of the barker ring substantially equidistantly, and their inner cutting ends project inward beyond the cylindrical surface of the throat 7.

The preferred shape of the cutter bit 13 is shown in detail in FIGS. 5, 6 and 7. Each bit is of trapezoidal cross section, as 10 shown in FIG. 7, having two parallel sides 13a and 13b disposed in planes parallel to the axis of the barker ring, a side 13c perpendicular to such parallel sides and in contiguous engagement with collar 12 and an inclined face 14a. The face 14a of the bit connecting such parallel sides is inclined relative 15 to them in a direction such that the leading side of the bit in the direction of barker rotor rotation is wider than the trailing side of the bit. Consequently, the leading face 13b of the bit and such inclined joining face 14a converge to form an acute-angled angled cutting edge 15a which preferably is approximately 20 60°.

The inner end of the bit is beveled to provide an end surface 14b, shown in FIGS. 5 and 6, which will form a cutting edge 15b that is substantially parallel to the axis of the rotary ring. The bevel between the leading face 13b of the bit and the bit 25 end face 14b again is such that the angle of the cutting edge 15b is acute and preferably about 60°. The two cutting edges 15a and 15b intersect to form an obtuse-angled corner 15c, having an angle between 120° and 135°, depending upon the slope of the inner face of collar 12. Such angle preferably is 30 approximately 125°.

As a log L is fed by the conveyor 1 into the mouth of the barker ring as shown in FIG. 1, the cutting edges 15a and 15b will engage and trim off any branch stubs or other protuberances projecting outward to a distance beyond the circle defined cooperatively by the cutting edges 15b of the several bits. A sufficient number of these bits should be provided to cut such projections effectively, and sixteen of such bits has been found to be a satisfactory number. Disposition of the 35 lengths of the cutting bits substantially in radial planes of the barker rotor parallel to the axis of the rotor provides a strong cutting end, and one which does an effective cutting job. In particular, a long cutting edge is afforded by arranging the cutting edge sections 15a and 15b at an obtuse angle, as shown 40 best in FIG. 6, instead of the cutting edge sections forming a right angle like the cutting edge sections of the cutter bits 45 shown in the prior Nicholson U.S. Pat. No. 2,802,494.

The limb refuse cut by the bits 13 and the bark refuse scraped from the log by the barker arms 8 in the form of discrete fragments falls into the circular pit 16 shown in FIGS. 1 and 8, which is located directly beneath the barker. Across the lower portion of this pit extends a bridge 17 which may be in the form of a channel having its edge flanges extending upwardly. This bridge preferably extends diametrically across 55 the pit so that it serves to support a bearing for the upper end of an upright shaft 18 located centrally of the pit. This shaft carries a hub 19 on which is mounted a rotor disk 20 of a hog.

The upright shaft 18 carries a pulley 21 which is connected by several V-belts 22 to a drive pulley 23. This drive pulley 60 can be driven by any suitable drive mechanism such as represented by a shaft 24. The size of the pulleys 21 and 23 will be selected in accordance with the speed of rotation of the drive shaft 24 and the speed at which it is desired to have the hog rotor rotate.

65 On opposite sides and opposite ends of the bridge 17 are mounted stationary shearing bars 25, the lower edges of which constitute shearing edges. Movable shearing bars 26 are carried by the rotor plate 20 in positions to coact with the stationary shearing bars 25 as the rotor rotates. In order to effect 70 a slicing relationship rather than a chopping relationship between the movable and stationary shearing bars, such movable and stationary shearing bars are mounted so that the shearing edge of each moving bar approaches the shearing edge of a stationary bar at an acute angle rather than parallel to the shearing edge of the stationary bar.

To attain such acute-angled relationship of the shearing bar edges, the bridge 17 is made of substantial width and the stationary shearing bars 25 are mounted chordwise on the edges of the bridge toward the approaching movable shearing bars 26. While such movable shearing bars are disposed substantially radially of the rotor disk 20, their shearing edges are shown in FIG. 8 as being located somewhat forward, in the direction of rotor rotation, of the radius which passes lengthwise through the bar, in each instance. Consequently, when the shearing edges of a movable bar and a stationary bar move into shearing relationship as shown in FIG. 9, such edges are disposed at an acute angle.

The rotor plate 20 is spaced downward somewhat from the lower shearing edges of the stationary shearing bars 25 as shown in FIG. 1. Immediately ahead of each movable shearing bar 26, the rotor plate 20 has a slot 27 through it for passage of hogged waste material from above such plate down into the lower portion of the hog. Beneath each movable shearing bar 26 is a vane 28 extending radially of the rotor, which acts to sweep the hogged waste material rotationally within the casing of the hog including an upright circumferential wall 29, preferably of considerably greater extent than the wall of the pit 16, a bottom wall 30 and an annular top wall 31 bridging between the pit and the circumferential wall 29 of the hog.

While the number of movable shearing blades and vanes and the speed of their rotation are not critical, it is preferred that there be from three to six of such shearing bars and vanes, four being shown in the drawings as preferred. The speed of rotation of the rotor should be sufficiently great to provide an effective quick shearing action for bark and limb refuse dropping into the hog onto plate 20. The speed of rotation of the vanes 28 should be great enough so that they will be effective to sweep the hogged material out of the hog casing through a discharge opening 32, which opens tangentially of the casing, both by physical contact of the vanes with such material and by the air current generated by such vanes. The force produced on the air by the vanes discharges such air through opening 32 so that air is drawn down through the pit 16 and the slots 27 in the plate 20 and carries the hogged material with it.

To prevent limb and bark refuse from lodging on the bridge 17, it is preferred that it be capped by a ridged cover 33 held in place by bolts 34. The ridge shape of such cover deters accumulation of refuse on the bridge, but in addition, flow of air drawn through the hog by movement of the vanes 28 will tend to sweep downward past opposite sides of the bridge and remove material from the ridged cover.

Because of the air flow through the hog, discrete bark and limb refuse fragments dropping into the hog onto plate 20 are 50

air-borne to a greater or lesser extent. Since such refuse can only pass through the rotor plate 20 by way of the slots 27 immediately ahead of the moving shearing bars 26, the current of air will tend to blow the waste material fragments from the surface of plate 20 against the leading sides of such bars, to feed the discrete wood refuse fragments between the coating stationary shearing bars 25 and rotary shearing bars 26. Also, rotational movement of the bars 26 will tend to move them against material falling into the hog. The combination of these acts enables the moving shearing bars to force at least most of the waste material against the stationary shearing bars to reduce the size of the discrete wood refuse fragments farther before they drop through the slots 27. Consequently, the waste material is hogged sufficiently fine so that it can be propelled readily from the hog by the vanes 28 through the discharge opening 32, and such hogged material will be suitable for use as a mulch or for other disposal, such as for fuel.

I claim:

1. Refuse-reducing mechanism for a log barker having a rotary barker ring through which a log can be fed lengthwise, comprising a flange flaring outwardly from the infeed side of the barker ring and carried thereby, a plurality of cutter bits carried by said flaring flange for cutting limb stubs from a log moving through the barker ring, and a hog located beneath the barker ring, receiving limb material cut by said cutter bits and reducing farther the size of such material.
2. The refuse-reducing mechanism defined in claim 1, in which each cutter bit is disposed in substantially a radial plane of the barker ring and has a cutting edge including a first section on the end of the bit extending substantially parallel to the axis of the barker ring and a second section inclined outwardly from said first section toward the feed end of the barker ring, said two cutting edge sections being disposed at an obtuse angle.
3. The refuse-reducing mechanism defined in claim 2, in which the obtuse angle between the two cutting edge sections of each bit is approximately 125°.

4. The refuse-reducing mechanism defined in claim 1, in which the hog includes stationary and movable shearing bars having shearing edges and means moving said movable shearing bars relative to said stationary shearing bars so that the shearing edge of each movable bar moves across the shearing edge of each stationary bar at an acute angle thereto.

5. The refuse-reducing mechanism defined in claim 1, in which the hog has a stationary shearing bar and a rotor including a plate, movable shearing bars carried by said plate for movement relative to said stationary shearing bars and vanes carried by said plate and movable thereby to sweep out of the hog material sheared by said shearing bars.
